UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,573, dated August 21, 1894.

Application filed July 28, 1894. Serial No. 518,892. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls forming a series of panels with 10 upright ornamental figures arranged in the center of said panels and festoons of flowers hanging from, and connecting said scrolls, as represented in the accompanying drawing. The border or upper portion of the design is 15 formed of lyre-shaped ornaments with upright

ornamental figures in the center and drooping ornaments formed of ornamental leaves connecting said lyre-shaped ornaments as shown.

What I claim is—

- 20 1. The design for wall paper herein shown and described.
2. In the design for wall paper the border herein shown and described.

Witness my hand this 26th day of July, 25 1894.

CHARLES BOOZE.
